UNITED STATES PATENT OFFICE.

ALFRED SCHWARZ, OF UPPER MONTCLAIR, NEW JERSEY, ASSIGNOR TO COAL AND OIL PRODUCTS CORPORATION, A CORPORATION OF DELAWARE.

OIL-CRACKING PROCESS.

Application filed March 25, 1925. Serial No. 18,076.

This invention relates to a process of cracking oil thereby producing lighter oils and gas therefrom. It relates more particularly to a process by which the oils may 5 be cracked and the carbon resulting therefrom can be utilized in the process.

In processes now commonly used for producing motor fuels from oils that have higher boiling points than those suitable for 10 motor fuels, which processes are called oil cracking processes, it is more or less common practice to crack the oils thereby producing residues in the form of coke or heavy tars of little commercial value which are often- 15 times expensive to handle and hard to remove from the apparatus in which they are produced. Furthermore, in cracking oils the heat transfer is usually made through the walls of receptacles which procedure is 20 wasteful and frequently causes deposition of carbonaceous matter upon the heating surfaces.

One of the objects of my invention is to crack oils in such a manner that practically 25 all of the heat supplied to the oil is introduced directly into the oil without passing through the walls of the receptacle. Another object of my invention is to so control the chemical composition of the gases pro- 30 duced as to have a maximum of compounds of a hydrocarbon series other than the paraffin series, and preferably those of the benzol series. A further object of my invention is to consume the residue formed during the 35 operation so as to generate heat and gases in order to eliminate the handling of residues and in order to be able to crack substantially all the oil and to convert any such portion of the oil that may have a tendency to be 40 precipitated as carbon, into a fixed gas, this gas being a secondary product of the process.

The invention will be understood from the description in connection with the accom- 45 panying drawings, in which two arrangements of apparatus are shown by which the process can be performed. In the draw- 50 ings, Fig. 1 is a somewhat diagrammatic view showing the arrangement of the appa- ratus, parts being shown in section, to carry out the process and Fig. 2 is a similar view showing a modified arrangement of appa- 55 ratus.

In the drawings, reference character 1 in- 60 dicates a gas producer somewhat similar to

those commonly used, the same being modified, however, so as to adapt it especially for carrying out the present invention. The producer 1 has a main chamber 2 which may be lined with fire-brick, and a superposed 60 chamber 3 having a waste heat duct 4 ex- tending therefrom provided with a valve 5. The chamber 3 is closed at the top by a cover 6 which carries a perforated plate to serve as an oil distributor as indicated below. A 65 coal hopper 7 controlled by a valve 8 leads to the chamber 3 and the hopper 7 is sup- plied from a supply 9 that is provided with a valve 10 that may be opened and closed at will for feeding a charge of coal to the 70 hopper 7.

The producer 1 is also provided with a grate 11 below which steam may be intro- 75 duced into the producer through the valve controlled inlet pipe 12 from any convenient source. A valved pipe 13 leads from the producer 1 tangentially into a settling cham- 80 ber 14 that is provided with an outlet pipe 15 controlled by the valve 16. A pipe 17 leads from upper portion of the settler 14 to a fractionating tower 18 which is pro- 85 vided with the usual shelves 19. This frac- tionating tower may also be filled, if desired, with porous material such as coke, broken brick or the like. Reflux pipes, one of 90 which is shown at 22, lead from the shelves to the lower end of the fractionating tower and a valved branch pipe 23 leads from the pipe 22 into the tower and a valved branch 95 24 may lead to a storage or supply tank. A pipe 25 leads from the fractionat- 100 ing tower 18 to a condenser 26 that may be cooled in any convenient manner. A pipe 28 leads from this condenser to a tank 29 that is provided with valved overflows or drains 30 and 31. A pipe 34 leads from the tank 29 through a pump 35 to a gas holder not shown. If desired two producers 1 may be connected to the tower 18, the same being 105 operated alternately.

A branch pipe 39 provided with a valve 43 leads from the pipe 12 to the injector 40. The suction end of the injector 40 is connected by a valved pipe 41 to the supply tank 42 for oil that is to be cracked. A 110 pipe 46 leads from the injector 40 to the cover cap 6. The oil from tank 42 may be forced into the gas producer 1 by means of the injector 40 when gravity feed is not pro- 115 vided or a pump may feed the same. The

discharge from pipe 15 of separator 14 and from the pipe 20 of the fractionating tower 18 may be introduced into the supply tank 42 if desired. A blower 47 may be used for 5 starting the fire in the producer 1.

In the modification shown in Fig. 2 many of the devices are identical with those already described in connection with Fig. 1 and such parts are indicated by the same reference character with the suffix "a". This arrangement differs in certain respects from that shown in Fig. 1. The outlet pipe 4^a leads into a heating chamber 50 in which a still 53 is placed. This still is provided with 15 tubes 51 which tubes lead to a stack 52. A valved pipe 55 leads from the still 53 to the valved pipe 17^a, that leads directly from the gas producer 1^a to the fractionating tower 18^a, the tower 18^a being provided with 20 a vapor outlet 25^a in the upper portion thereof. One or more valved reflux pipes 22^a lead from the shelves 19^a to points below the liquid level in still 53. Two or more gas producers 1^a may be connected to the still 25 53 and the fractionating tower 18^a and operated alternately. A pipe 41^a leads from near the bottom of the still 53 through a pump 57 to an injector 40^a. Steam may be admitted to the injector 40^a through the 30 pipe 39^a from any convenient source and a pipe 46^a leads from the injector to the cap 6^a of the gas producer.

The upper end of the tower 18 or 18^a may be jacketed and the supply of water thereto 35 may be controlled or regulated by means of valves as shown at 60 so as to introduce steam or water around the upper portion thereof.

The process may be operated in two ways 40 which may be termed "continuous" and "intermittent" respectively. In operating by the so-called continuous method, fire is started in the producer 1 on the grate 11, coal or coke being then charged into the 45 chamber 2 until it is filled nearly to the valve 8. The blower 47 is started with the valve 5 open and the valves 8, 36, 38, 43, 44 and 45 closed. The fire is blown until the 50 temperature near the top of the coke or coal reaches approximately 700 to 1000° F. When this temperature is reached the valve 5 is closed, the valve 38 is opened and the pump 35 is started. The vacuum created by this pump will take in air through 55 the blower 47 controlled by the valve 49 and superheated steam is admitted through valve 44 into the injector 40, while oil is admitted from the tank 42 into the injector 40 so that the atomized mixtures are 60 sprayed through the cap 6 into the chamber 2 where the coal in the upper part of the producer acts as a temporary retainer for the oil and the high temperature in this region will begin to crack the oil. The 65 vapors therefrom will pass downwardly into

a hotter region where more cracking will take place and carbon will be deposited, the vapors or gaseous products finally passing into the pipe 13 and through the settling chamber 14 where suspended particles will 70 be deposited and the vapors will then pass through a pipe 17 into the column 18 where the vapors are fractionated, the uncondensed portion passing through pipe 25 and condenser 26 whereupon the uncondensed gases 75 and the condensate pass into the receiving tank 29 where the water settles to the bottom and is withdrawn through the pipe 30 while the oil is withdrawn through the pipe 31 and the fixed gases pass through the pipe 80 34 and pump 35 to a place of consumption or to a gas holder. The reflux pipe 22 is arranged to lead the reflux from a plate 19 to the base of the tower where it can be introduced into the hotter portion of the tower 85 through the pipe 23, or it may be withdrawn through the pipe 24. When introduced into the hotter portion of the fractionating tower 18, the condensate comes into contact with the hot gases from producer 90 1 whereby additional cracking takes place. More than one reflux line 22 may be used, leading from different plates 19. When a plurality of reflux lines are used to lead 95 from separate plates 19, the condensates passed therethrough will be oils of different specific gravities and different qualities which may be subjected to further treatment in the tower 18, or they may be withdrawn from the system for other uses. The lighter 100 oils will, of course, be drawn from the top shelves 19 of the fractionator and heavy oils from lower shelves. The heavy oils that may be withdrawn through the pipe 20 may be passed through the system again by first 105 introducing the same into the supply tank 42. While operating the process as above described, air is constantly taken into the system which is first caused to produce carbon dioxide in the lower part of the gas producer and when the proper amount of air is introduced this carbon dioxide is converted into carbon monoxide in upper layers 110 of the incandescent coal or coke. Superheated steam is admitted through the pipe 115 12, and forms water gas in accordance with the well known reaction and the combined gases meet the oil vapors that pass downwardly through the upper portion of the producer and the mixture passes through 120 the line 13 as above indicated. Reactions appear to take place between the gases and vapors, but on account of the fact that there are so many different hydrocarbons present in the mineral oil vapors, the reactions of 125 which are very complicated, it is not certain what the various chemical reactions are in the different reaction zones.

The following is given as an illustration of results that have actually been obtained 130

with an installation of this character. With a gas producer 1, about 7' high and 14" in internal diameter and a fractionating tower 18, about 14' high and 12" in diameter arranged as illustrated in Fig. 1, I charged the producer with ordinary foundry coke and raised the temperature to about 800° F. and charged superheated steam through pipe 12 at a temperature of about 600° F. 5 A vacuum pump of the eccentric piston type was set in operation as shown at 35 and a small amount of air was admitted through the valve 49. Petroleum oil having a boiling point such that about 12% could be distilled off between 500° F. and 600° F., the remainder boiling above 600° F., was introduced through the injector 40 through the spray box 6. This oil was the residue from a pressure cracking operation commonly 10 called "pressure still tar" in the trade. The process was operated for several hours and during that entire time gases obtained from the receiver 29 burned with a high calorific value and distillates collected from the pipe 15 25 contained 65% of material that was distilled off between 120° F. and 437° F. and 60% of the remainder distilled below 600° F.

When operating the process as just described, due to the continuous admission of air, there appears to be a considerable amount of hydrocarbon derivatives formed of the fatty acid series. And this constitutes an important factor in the process. Such fatty acids may be refined and used for many 30 35 purposes, for example: Manufacture of soap requires large quantities. If the process is operated with a view of making fatty acids as a by-product the continuous admission of air is desirable. If however the process is operated more for the purpose of making motor fuel, a large amount of fatty acids in the distillate is not desirable. When it is desirable to avoid the production of fatty acids, the process may be operated intermittently by first blowing air by means of the pump 47 through the gas producer 1 and permitting the products of combustion to pass out through the pipe 4 until the temperature has reached the proper point after 40 45 50 which the air can be shut off and the oil sprayed in and steam admitted until the temperature needs to be increased again. Another variation of my process is that I may mix the oil with ordinary live steam and pass both of them through a superheater and then introduce this mixture into the distributor #6. When the process is operated without an air supply, during the time the oil is being admitted to the producer 1, the 55 60 65 production of fatty acids is very nominal but during the time that air is being blown into the producer to raise the temperature of the carbon therein to incandescence, a certain amount of heat would be wasted but I utilize such heat, by arranging the apparatus

as indicated in Fig. 2. The products of combustion pass in this arrangement of apparatus through the pipe 4^a into the fire box 50 along the under side of the still 53, which contains oil to be cracked, and these products 70 then pass through the tubes 51 where they give up further heat to the oil and these products of combustion finally pass out through the stack 52. Vapors from the oil in the still 53 pass through the pipe 55 to 75 the tower 18^a and uncondensed vapors issue from the tower through pipe 25^a. Reflux condensate passes through the pipe or pipes 22^a from the tower 18^a into the still below the liquid level therein. After the air has 80 been blown into gas producer 1^a a sufficiently long time to bring the temperature to that of incandescence, the air is shut off and oil is passed by means of the pump 57 from the still or heater 53 through the pipe 85 46^a into the spray box 6^a. Superheated steam may at the same time be admitted through the pipe 39^a and injector 40^a to the gas producer 1^a.

While I have described the process as being conducted with the aid of steam which is preferably superheated, I do not limit myself to the use of steam as I may carry out the process without using steam by merely producing carbon monoxide gas and relying upon the reactions among the hydrocarbon vapors, the gas being used as a medium of heat transfer. The process is adaptable to many grades of oil and the reactions will vary with the sort of hydrocarbons used. 90 Not only very heavy oils and residues may be used as the stock to be cracked, but light oils such as kerosene and gas oil may also be treated by this process. At the same time other sorts of oils such as coke oven light 95 oil, coal tar and the like may be introduced into the producer and may be subjected to the treatment above described.

While the most logical method of supplying heat to the oil vapors and water vapors for the purpose of inter-reaction, is to abstract said heat from the gas producer, nothing herein contained shall be construed to limit the scope of this invention by the additional application of external heat on any portion of the apparatus. While I primarily intend to extract the combustible products from the fixed gases, in some cases I may desire to conduct the mixed product to a burner or internal combustion engine 110 115 120 and use all the products direct.

I claim:

1. The process which comprises heating portions of a mass of carbon to different temperatures by combustion, bringing steam into contact with a portion hot enough to form water gas, simultaneously bringing hydrocarbon oils into contact with portions sufficiently heated to form oil vapors, maintaining said vapors in contact with said 125 130

mass of carbon, passing the same through zones of said mass of carbon of increasing temperatures sufficiently hot to crack said vapors and produce a substantial amount 5 of condensable hydrocarbons and sufficiently cool to avoid complete gasification, mixing the water gas and oil vapors at high temperature and segregating the gaseous and condensable products.

- 10 2. The process which comprises heating a mass of carbonaceous material to an oil cracking temperature thereby producing waste gases, utilizing said waste gases to heat a body of oil to a distilling temperature, 15 removing vapors from said body of oil, introducing unvaporized oil from said body into said mass of carbonaceous material to effect vaporization thereof, passing the resultant vapors downwardly through zones 20 of increasing temperature to crack the same,

fractionating the resultant vapors and gases, and conducting heavier condensed fractions to said body of oil for retreatment.

3. The process which comprises establishing a gas generating zone by blowing hot 25 carbonaceous material with air, heating a body of oil to a distilling temperature by means of hot gases resulting from said blowing, removing vapors from said body, conducting unvaporized oil from said body to said gas generating zone for vaporization therein, passing resultant vapors downwardly through said zone to effect cracking thereof, removing vapors and gases from said zone, fractionally condensing the vapors, and returning heavier condensates to said body 30 of oil for retreatment.

In testimony whereof I affix my signature.

ALFRED SCHWARZ.
